GAS RETORT

Filed July 7, 1921

FIG. 2.

FIG. 3.

Inventor:

Heinrich Koppers,

65: Monday, Clarke & Campbell
in Atty's:

UNITED STATES PATENT OFFICE.

HEINRICH KOPPERS, OF ESSEN-RUHR, GERMANY, ASSIGNOR TO THE KOPPERS DEVELOPMENT CORPORATION, OF PITTSBURGH, PENNSYLVANIA, A CORPORATION OF PENNSYLVANIA.

GAS RETORT.

Application filed July 7, 1921, Serial No. 483,049, and in Germany September 1, 1919.

(GRANTED UNDER THE PROVISIONS OF THE ACT OF MARCH 3, 1921, 41 STAT. L., 1813.)

This invention relates to retort ovens and especially to gas retorts of the type which embodies a plurality of retorts assembled in a joint envelope.

According to the invention, the distributing channels running along above the regenerators alternate regularly with each other in their task as air and gas distributors; this results in the first place in a division into two parts of what according to another invention of mine is a single air channel, so that the nozzles assigned to these two channels can be regulated independently from the very first. Of the four distributing channels belonging to each heat pair of regenerators the outer ones communicate directly, by vertical shafts, with the regenerators lying underneath, while the inner channels communicate at any time with the respective regenerators by oblique shafts. This oblique arrangement of these shafts, in spite of the alternation in the arrangement of the gas and air distributing channels, renders possible a connection with the respective regenerators, while owing to the vertical or at most, the slight slanting arrangement of the distributing shafts the drawbacks of the horizontal cross channels heretofore used are avoided. Furthermore, the entire arrangement makes it possible withal to at least diminish the lack of symmetry hitherto felt by allowing the distributing channels to be made of practically equal value as regards the resistance, whereby the basic distribution of the fuels, gas and air, is promoted.

In addition to the general objects recited above, the invention has for further objects such other improvements or advantages in construction and operation as are found to obtain in the structures and devices herein-after described or claimed.

In the accompanying drawings, forming a part of this specification and showing, for purposes of exemplification, a preferred form and manner in which the invention may be embodied and practised, but without limiting the claimed invention specifically to such illustrative instance or instances:—

Figure 1 is a vertical section taken transversely of the retort chambers of a retort oven constructed in accordance with the improvements of the present invention; and

Figure 2 is another vertical section of the same but taken in a plane extending longitudinally of the retort chambers.

Fig. 3 is a partial sectional view similar to Fig. 2 but showing the partition 29 in the channels 25.

In the drawing belonging hereto such an oven is reproduced in illustration 1 by a section vertical to the retort axis, in illustration 2 by a section parallel to the same.

Under the retorts arranged in the joint envelope 10, for which regular heating flues are created by cross partitions 12, the regenerators 13 for air and 14 for gas are provided, of which the former are placed on the inside, the latter on the outside. Above each regenerator the four distributing channels, i. e. 21 for gas and 25 for air, run along, which communicate with nozzle-shaped perforations 23 or 27 that terminate in the different heating flues. The channels 21, on the other side, communicate with the gas regenerator 14 through the shafts 23', the channels 25 through the shafts 27' with the air regenerators 13. In this connection the outer shafts run simply vertical, while the inner ones are arranged in slanting positions.

The longitudinal through channels 21 and 25 can be reached from the front sides of the retort group, so that on the one hand the regulation of the slides above the channels 23' and 27' for the uniform distribution of gas and air is possible and also on the other hand it is feasible to effect a cleaning in case of obstructions. In this connection, this arrangement can be used uniformly for horizontal and slanting retorts. In connection with the latter, as well as with very long horizontal retorts, it is advisable to separate the distributing channels in the center by means of a partition such as shown at 29 in Fig. 3 and to arrange in the front and rear oven halves resulting thereby i. e. on each side of partition 29 an equal number of connecting channels 23' and 27' going to the heat storers situated underneath, whereby from the very first a basic distribution is created which can be made more close by the regulating slides.

With a further subdivision of these longitudinal channels by several partitions, the slides lying between any two such partitions

are adjusted from the outside by openings in the partitions, these openings being susceptible of being closed. By this dissolution into four longitudinal channels with distributing slides for each pair of heat storers a practically exact admission to the different burners is now possible. The distribution lengthwise is accomplished by a suitable regulation of the slides of each longitudinal channel among themselves, and the distribution as regards the central and outside flues by the varying degrees of throttling of the longitudinal channels with reference to each other.

15 10 I claim:

1. A gas retort construction comprising a horizontal series of substantially parallel substantially horizontal retorts, a group of vertical flues along each of the two opposite 20 lateral sides of each of said retorts, a group of flues over each of said retorts communicating with the flues on both lateral sides thereof respectively, a substantially horizontal bus channel below each of the groups of vertical flues communicating with said vertical flues thereabove at the lower parts thereof, a regenerator below each of the bus channels communicating with the bus channel thereabove by a plurality of separate ducts spaced 25 from each other along the bus channel with which said ducts communicate.
2. A gas retort as claimed in claim 1 combined with means in each of said bus channels for varying the relative flow of gas in 30 different portions thereof.

3. A gas retort construction comprising, in combination: a horizontal series of substantially parallel elongated retorts; a group of vertical flues along each of the two opposite lateral sides of each of said retorts, a flow 40 duct means extending continuously over all of said retorts and communicating with the flues on both lateral sides thereof respectively; a pair of bus channels below each of the groups of vertical flues communicating with the vertical flues thereabove at the lower parts thereof; a regenerator below each pair of the bus channels communicating with one of the bus channels of the pair of bus channels thereabove by a plurality of separate 45 ducts spaced from each other along the bus channel with which said ducts communicate and communicating also with one of the bus channels of the pair of bus channels above an adjacent regenerator by a plurality of 50 separate ducts spaced from each other along the bus channel with which said ducts communicate.

4. A retort oven according to claim 3, characterized by means in said bus channels for 55 regulating the flow from the regenerator communicating therewith, and further characterized by each of said bus channels having a transverse partition lying between two of said ducts communicating therewith.

5. Retort oven according to claim 3 characterized by means in said bus channels for regulating the flow from the regenerators communicating therewith.

HEINRICH KOPPERS.
